UNITED STATES PATENT OFFICE.

JOHN F. STENDER, OF CHICAGO, ILLINOIS, ASSIGNOR TO THE ADAMS & WESTLAKE COMPANY, A CORPORATION OF ILLINOIS.

INSTRUMENT-LAMP.

1,034,936.

Specification of Letters Patent.

Patented Aug. 6, 1912.

Application filed March 14, 1912. Serial No. 683,820.

To all whom it may concern:

Be it known that I, JOHN F. STENDER, a citizen of the United States, and resident of Chicago, county of Cook, and State of Illinois, have invented certain new and useful Improvements in Instrument-Lamps, of which the following is a specification, and which are illustrated in the accompanying drawings, forming a part thereof.

10 The invention relates to lamps adapted for attachment to the dash-board of an automobile for illuminating instruments, such as gages, speed indicators, etc.; its object being to provide a simple and compact lamp 15 which may be secured directly to the dash-board; and it consists of a device such as is hereinafter described and as illustrated in the accompanying drawings, in which—

Figure 1 is a longitudinal sectional view 20 of the lamp as applied to a dash-board; Fig. 2 is a sectional view on the line 2—2 of Fig. 1; and Fig. 3 is a side view of the hood for inclosing the lamp.

The dashboard of an automobile is shown 25 at 10. The lamp consists of an incandescent electric bulb 11, carried by a suitable socket 12. The socket 12 is housed within a casing 13 having a rearwardly extending shank portion 14 adapted to project through the 30 dashboard and having its outer end externally threaded to receive a binding nut 15. The shell 13 is provided with a circumferential flange 16 adapted to fit against the inner face of the dashboard, so that when 35 the nut 15 is turned up the lamp is securely held in place. A pocket 17 projecting laterally from the aperture in the dashboard accommodates a stud 18 projecting laterally from the shank 14 of the socket 40 casing, and holds the same against rotation.

The lamp socket presents no novel electrical features, but is adapted to receive a line plug 19 in its rearward end.

45 A hood or shield 20 incloses the bulb 11, and is in the form of a tubular cap adapted to fit over the shell 12, and is held therewith by means of a spring stud 21 housed within and projecting through the side wall of the 50 shell and entering a suitable aperture in the hood. The outer end of this stud is rounded, thereby permitting the hood to be forced over it either in applying it to or removing

it from the socket shell. A light-emitting aperture 22 is provided in the hood to 55 throw a beam of light from the lamp in the desired direction.

I claim as my invention—

1. An instrument lamp comprising, in combination, a bulb socket, a casing inclosing the socket and having a rearwardly extending threaded shank adapted to enter an aperture in a support, and a circumferential flange, means for preventing the casing from turning in its support and a clamping 60 nut engaging the threaded end of the shank. 65

2. An instrument lamp comprising, in combination, a bulb socket, a casing inclosing the socket and having a rearwardly extending threaded shank and a circumferential 70 flange and a laterally projecting stud back of the flange, and a clamping nut engaging the threaded end of the shank.

3. An instrument lamp comprising, in combination, a bulb carrying socket adapted 75 to receive an electric circuit terminal plug in its rearward end, a casing inclosing the socket and having a backwardly-extending threaded shank adapted to enter an aperture in a support, and a circumferential 80 flange, means for preventing the casing from turning in its support and a clamping nut fitting upon the threaded end of the shank.

4. An instrument lamp comprising, in 85 combination, a bulb socket, a casing inclosing the socket and having a rearwardly extending threaded shank and a circumferential flange, a clamping nut engaging the threaded end of the shank, and a hood having a light-emitting aperture sleeved upon the forward end of the casing. 90 95

5. An instrument lamp comprising, in combination, a bulb socket, a casing inclosing the socket and having a rearwardly extending threaded shank and a circumferential flange, a clamping nut engaging the threaded end of the shank, a hood having a light-emitting aperture sleeved upon the forward end of the casing, and a spring 100 stud carried by the casing for engaging the hood.

JOHN F. STENDER.
